UNITED STATES PATENT OFFICE.

JOHN C. ROSS, OF AKRON, OHIO.

FORCE-FEED LUBRICATOR.

1,270,440.

Specification of Letters Patent. Patented June 25, 1918.

Application filed March 27, 1917. Serial No. 157,727.

To all whom it may concern:

Be it known that I, JOHN C. ROSS, a citizen of the United States, residing at Akron, in the county of Summit and State of Ohio, have invented certain new and useful Improvements in Force-Feed Lubricators, of which the following is a specification

This invention relates to an improved force feed lubricator and has as its primary object to provide a device of this character which will be mechanically operated for pumping different kinds or grades of lubricants from different supply tanks therefor and forcing the lubricants to their respective points of discharge.

The invention has as a further object to provide a novel arrangement wherein the lubricants upon being pumped from the supply tanks therefor will be heated so that the said lubricants will be maintained fluent and wherein the lubricants will be discharged through pipes carried along a steam line to maintain the lubricants heated until finally discharged.

A further object of the invention is to provide a device of this character having a number of feeds for supplying each of the separate lubricants to be delivered by the device so that the lubricator will thus be adapted to oil a corresponding number of parts and wherein the pumps employed in connection with all of the said feeds as well as the pumps for drawing the lubricants from the supply tanks, will all be mounted upon common reciprocating members to be simultaneously operated thereby.

A further object of the invention is to provide a lubricator wherein the flow of the lubricant may be manually adjusted and wherein any excess lubricant drawn up by the pumps will be automatically returned to the respective supply tanks therefor.

And the invention has as a still further object to provide a lubricator of the above described character having an improved mechanism for reciprocating the pump pistons of the device.

Other and incidental objects will appear as the description proceeds and in the drawings wherein I have illustrated the pre-

ferred embodiment of the invention and wherein similar reference characters designate corresponding parts throughout the several views:

Figure 1 is a fragmentary plan view of my improved lubricator particularly showing the mounting of the pump pistons of the device, 55

Fig. 2 is a longitudinal sectional view particularly showing the pawl and ratchet gear employed for rotating the cam shaft of the lubricator, 60

Fig. 3 is a longitudinal sectional view taken on the line 3—3 of Fig. 1 and showing the arrangement of the cam yokes employed 65 and the mounting of the cam to cooperate with the said yokes for actuating the pump pistons of the lubricator,

Fig. 4 is a transverse sectional view taken on the line 4—4 of Fig. 1 and particularly 70 showing the construction of the cams and illustrating the manner in which the discharge pipes from the lubricator are carried along a steam line for maintaining the lubricant within the said pipes heated,

Fig. 5 is a fragmentary sectional view showing one of the manifolds of the device,

Fig. 6 is a detail sectional view taken on the line 6—6 of Fig. 4 and illustrating the check valve employed in each of the supply 80 pipes leading to the pumps respectively,

Fig. 7 is a fragmentary plan view showing a modification of the invention wherein the pump pistons of the device are mounted directly within the lubricant tank, 85

Fig. 8 is a longitudinal sectional view of the modified construction particularly showing the pump employed and the overflow from the feed manifold,

Fig. 9 is a transverse sectional view taken on the line 9—9 of Fig. 8 particularly showing the construction of the cross head employed to carry the pump pistons, 90

Fig. 10 is a fragmentary sectional view illustrating the arrangement of the discharge 95 pipes in connection with the modified form of the invention,

Fig. 10^a is a fragmentary plan view of the pipes shown in Fig. 10.

Fig. 11 is a fragmentary plan view of a 100

still further modification of the invention, and

Fig. 12 is a fragmentary longitudinal sectional view of the form of the invention 5 illustrated in Fig. 11.

In carrying out the invention, my improved lubricator is formed with a suitable base 10 upon which is mounted oppositely disposed supplemental pump mechanisms 10 indicated as a whole by the numerals 11 and 12 respectively. These mechanisms are identical in construction and one thereof only will accordingly be described, the mechanism 11 being chosen. However, the reference numerals which will be used upon this mechanism 11 will also be used to designate corresponding parts in the mechanism 12.

Referring now more particularly to Figs. 1, 2, 3 and 4 of the drawings, the mechanism 20 11 includes a main body block 13 suitably connected to the base 10 to extend transversely thereof. Formed in the body block, adjacent its ends, are transverse pump chambers 14 and 14^a in which are mounted 25 to reciprocate the circulating pump pistons 15 and 16 respectively. Formed in the body block 13 between the chambers 14 and 14^a and arranged to extend substantially parallel thereto are a plurality of feed chambers 30 17 preferably six in number. Mounted to reciprocate within the chambers 17 are a plurality of feed pump pistons similar to the pistons 16 and three of which have been indicated at 18 while the other three have 35 been indicated at 19. The pistons 15, 16, 18 and 19 are all mounted to slide through suitable packing glands 20 threaded into the body block 13 and at their outer extremities, are connected by a transversely extending cross head or bar 21, with the pistons 40 loosely fitted through the said bar and screw threaded to receive nuts adjustably connecting the pistons with the bar.

Formed through the ends of the body 45 block 13 to communicate with the pump chambers 14 and 14^a are suitable passages in which are threaded supply pipes 22 and 23 respectively each having a check valve 24 interposed therein, as shown in detail in 50 Fig. 6, and also a cut-off valve 25. Connected with the supply pipes 22 and 23 are, as particularly shown in Figs. 4 and 5, up-standing overflow pipes 26 and 27 respectively. Interposed in the lower extremities 55 of these overflow pipes are spring pressed check valves 28, arranged with the valves movable downwardly against the tension of the springs thereof to open position. Mounted upon the upper ends of the overflow 60 pipes, are elbows 29 and extending between the said elbows are manifolds 30 and 31 respectively joined at their inner extremities by a nut or collar 32 closing the said manifolds at the adjacent ends thereof. Mount-

ed upon the elbows 29 to communicate with 65 the overflow pipes 26 and 27, are pressure domes 33 and 34 respectively.

Extending laterally and forwardly from the manifold 30 are, as particularly shown in Fig. 1, a plurality of feed pipes 35 extending over the body block 13, and projecting laterally and forwardly from the manifold 31, are a plurality of similar feed pipes 36 also extending over the body block, there being three of the feed pipes 35 as well 70 as three of the feed pipes 36. Connected to the outer ends of the said feed pipes, are elbows 37 having feed nozzles 38 extending downwardly therefrom. Screw threaded upon the lower extremities of the said 75 nozzles are flanged collars 39 receiving the upper extremities of sight tubes 40, the lower ends of which are fitted within suitable packing glands 41 screw threaded into the top of the body block 13 with the said 80 sight tubes communicating with passages leading into the feed chambers in the said block. The upper ends of the feed nozzles 38 are formed to provide valve seats and screw threaded upon the elbows 37 are a 85 plurality of manually adjustable valves arranged to coöperate with said seats, the valves associated with the pipes 35 being indicated at 42 while the valves associated with the pipes 36 are indicated at 43. 90

Screw threaded into the outer ends of the feed chambers 17 in the block 13 are a plurality of discharge pipes. The discharge pipes leading from the chambers of the pistons 18 are indicated at 44 while the discharge pipes leading from the chambers of the pistons 19 are indicated at 45. Mounted within the said discharge pipes, are a plurality of check valves 46 adapted to prevent a back-flow within the pipes. 100 Screw threaded into the outer extremities of the pump chambers 14, are feed pipes 47 and 48 respectively associated with the pumps 15 and 16. The feed pipes 47 and 48 are connected to the manifolds 30 and 31, 105 adjacent the outer ends thereof, and mounted within the said pipes are check valves 49 adapted to prevent a back-flow within the pipes. The discharge pipes 44 and 45 are carried away from the body block 13 in any preferred direction and, at their outer extremities, are arranged to parallel a steam line or pipe 50 leading from a suitable source of steam supply. Connecting the outer extremities of the discharge pipes with the 110 steam pipe 50, is a band 51. Any suitable number of these bands may be employed for holding the discharge pipes against the steam pipe 50 to be heated therefrom with the discharge pipes contacting with the pipe 115 50 throughout the greatest possible portion of their length up to the points of final discharge of the said discharge pipes. 120

Leading from the steam pipe 50 is a reduced branch steam pipe 52 which, as particularly shown in Figs. 4 and 5, is carried through the manifolds 30 and 31 and is provided, at its discharge end, with a shut-off valve 53. Interposed in the said steam pipe between the main steam line and the manifold 30, is a second shut-off valve 54.

It is now to be observed that the cross bars 21 of the mechanisms 11 and 12 are arranged in substantially parallel relation with the supply pipes 22 from the said mechanisms extending toward each other. Connected with the supply pipes 22 at one side of the base 10, is a suitable lubricant tank or container 55 and connected with the supply pipes 23 at the opposite side of the base is a similar tank or container 56.

Mounted between the cross heads is a cam gear for reciprocating the said cross heads and consequently reciprocating the several pistons connected thereto. This cam gear includes a driven shaft 57 mounted to extend transversely of the base 10 substantially midway between the blocks 13 and rotatably supported by suitable brackets 58 and 59 upstanding from the base. Keyed or otherwise secured upon the shaft 57 are cams 60. These cams each include, as particularly shown in Fig. 4, a cylindrical body 61 at one end of which is formed a radial flange 62. The opposite end of the body 61 is screw threaded to detachably receive a cap 63 having a radial flange 64 formed thereon to confront the flange 62. Rotatably mounted between the said flanges are a plurality of transversely extending anti-friction rollers 65 confronting the peripheral face of the body 61. Connected at their extremities to the cross bars 21 and arranged to coöperate with the cam 60 are yokes 66 disposed for engagement by the rollers 65 of the said cams for shifting the yokes to reciprocate the said bars.

Connected to the outer terminal of the shaft 57, is a rock arm 67 and mounted upon the adjacent extremity of the said shaft inwardly of the rock arm, is a ratchet 68 fixed to rotate with the shaft. Pivoted upon the upper end of the rock arm is a pawl 69 arranged to coöperate with the said ratchet. Consequently, actuation of the rock arm 67 will serve to rotate the shaft 57 by a step by step movement for reciprocating the cross bars 21. Freely mounted upon the shaft 57 inwardly of the ratchet 68, is a segment 70 upon one extremity of which is pivoted a pawl 71 arranged to coöperate with the ratchet 68 for holding the shaft 57 against retrograde movement. The opposite extremity of the segment 70 is formed with an arcuate slot 72 and projecting from the bracket 59 through the said slot is a suitable post receiving a nut 73 adjustable to bind

against the said segment. Therefore, as will be observed, the segment 70 may be adjustably rotated about the shaft 57 to position the pawl 71 in the path of the pawl 69. The pawl 69 will thus be caused to ride over the pawl 71 and the engagement between the pawl 69 and the ratchet 68 accordingly controlled for varying the stepped travel of the shaft 57. The arm 67 may be operatively connected with any suitable source of power for rocking the said arm.

In use, the tank 55 is preferably filled with one grade of lubricant while the tank 56 is filled with another grade of lubricant. With the valves 25 opened, lubricant from the tank 55 will, upon the reciprocation of the cross arms 21, in the manner previously described, be drawn out through the supply pipes 22 at one side of the base 10 by the circulating pump pistons 15 and into the pump chambers 14 while the lubricant within the tank 56 will be drawn out through the supply pipes 23 at the opposite side of the base by the circulating pump pistons 16 and into the pump chambers 14^a. The piston 15 will then operate to force the lubricant in the chambers 14 up through the pipes 47 and into the manifolds 30 while the pistons 16 will operate to force the lubricant in the pump chambers 14^a up through the pipes 48 into the manifolds 31. From the manifolds 30, the lubricant delivered by the pumps 14 will then be forced through the pipes 35 and through the nozzles 38 associated with the said pipes with the valves 42 operable for controlling the flow of the lubricant through the said nozzles and into the feed chambers 17 associated with the discharge pipes 44. The lubricant delivered by the pistons 16 will be forced from the manifolds 31 out through the pipes 36 and through the nozzles 38 associated with the said pipes with the valves 43 operable for controlling the flow of the lubricant through the said nozzles into the feed chambers 17 associated with the pipes 45. The feed of the lubricant from the nozzles 38 may thus be easily regulated and in this connection, it will be observed that the sight tubes 40 provide an easy means for accurately determining the flow of the lubricant. Lubricant deposited in the chambers 17 associated with the discharge pipes 44 will, as will be clear, be forced out of the said chambers and through the said pipes by the feed pump pistons 18 while lubricant entering the chambers 17 associated with the pipes 45 will be forced out of the said chambers and through the said pipes by the feed pump pistons 19. The different lubricants within the tanks 55 will thus be simultaneously drawn in and discharged without becoming mixed so that the device may thus be readily employed in any instance where it is desired to feed different grades or kinds

of lubricants simultaneously. Furthermore, it is to be observed that three discharge pipes or feeds for each lubricant are provided in connection with each pump mechanism.

- 5 When the device is thus being operated, the valves 53 and 54, within the branch steam pipes 52, are opened so that steam will flow through these pipes from the main steam pipe 50 and be carried through the 10 manifolds 30 and 31. The portions of the pipes 52 within the said manifolds will thus be kept hot and will heat the lubricant as it is delivered into the manifolds so that the lubricant will be rendered perfectly fluent to 15 be discharged through the nozzles 38. Since the discharge pipes 44 and 45 are carried along the main steam line 50, the lubricant in being forced through these discharge pipes will be again heated before being 20 finally discharged. I, therefore, provide an arrangement wherein the lubricant will be initially heated to render the lubricant fluent and will then be reheated before being delivered for use.
- 25 Attention is now directed to the fact that owing to the presence of the valves 42 and 43, a greater volume of lubricant may be discharged into the manifolds 30 and 31 by the circulating pump pistons 15 and 16 than 30 can flow past the valves and through the nozzles 38. Consequently, the overflow pipes 26 and 27 are provided. Excess lubricant in the manifolds 30 will be forced by the pistons 15 down through the overflow 35 pipes 26 and through the valves 28 associated with the said pipes to be returned into the supply pipes 22 from the tank 55 whence the lubricant was first drawn. In like manner, excess lubricant in the mani- 40 folds 31 will be forced by the pistons 16 down through the overflow pipes 27 and through the check valves 28 associated with the said pipes to be returned into the supply pipes 23 connected with the tank 45 56 whence the lubricant was first drawn. Overflow lubricant in the manifolds 30 and 31 will thus be returned to the respective tanks therefor and in this connection, it is to be observed that the air pressure in the 50 domes 33 and 34 will tend to equalize the tension of the springs of the check valves 28 so that these valves will readily respond to the pressure of excess lubricant in the manifolds 30 and 31 and permit such excess lubricant to readily flow past the valves back into the respective supply pipes therefor. Furthermore, it is to be observed that the pressure in the domes 33 and 34 will act to maintain a constant flow of lubricant 55 60 to feed nozzles 38 even though the lubricant pumps act intermittently.

In Figs. 7, 8, 9, and 10 of the drawings, I have illustrated a modification of the invention wherein an oblong lubricant recep-

tacle 74 is employed. Mounted to depend 65 into one end of the receptacle is a body block 75 and closing the said receptacle is a lid 76 secured in position by screws or other suitable fastening devices. Formed in the inner end of the block 75 is a circulating 70 pump chamber 77 in which is mounted to reciprocate a piston 78 slideable through a packing gland 79 screw threaded into the block. Connected with the bottom of the block and depending into the receptacle is 75 a supply pipe 80 communicating by a suitable passage 81 with the pump chamber 77 and having a check valve 82 mounted upon the lower end thereof. Fitted around the valve is a screen 83.

80 Formed in the block 75, at opposite sides of the pump chamber 77 and arranged substantially parallel thereto are feed pump chambers 84 in which are mounted to reciprocate pistons 85 slideable through packing glands 86 similar to the glands 79. Connected to the outer extremities of the pistons 78 and 85 is a transversely arranged cross bar or head 87 having the said pistons fitted through suitable notches therein, as 90 particularly shown in Fig. 9, and adjustably connected with the bar by a plurality of nuts.

95 Secured to the bar 87 is a yoke 88 having a supporting rod 89 extending laterally therefrom at the side of the yoke opposite to the said bar. The rod 88 is mounted to slide within a suitable boss or socket 90 projecting inwardly from the adjacent end wall of the receptacle 74 and closed at its outer 100 end by a plug 91 screw threaded into the said socket. Depending from the yoke is an extension 92, the lower end of which is slidably received between guides 93 up-standing from the bottom wall of the receptacle. The rod 89 and extension 92 are thus 105 adapted to rigidly support the yoke for reciprocatory movement.

Screw threaded into the upper extremity 110 of the passage 81 of the block 75 is a feed pipe 94 at the upper end of which is arranged a transversely extending manifold 95. Leading from this manifold is an overflow pipe 96 screw threaded into the block 75 and communicating with a passage 97 115 leading through the block. Mounted within the lower end of the said passage is a spring pressed check valve 98 shiftable downwardly to open position against the tension of the spring thereof. Connected with the 120 extremities of the manifold 95 are elbows 99 in which are fitted depending feed nozzles 100 and screw threaded upon the said nozzles are flanged collars 101 in which are mounted sight tubes 102 fitted, at their 125 lower ends, within suitable passages 103 formed in the block 75 to communicate with the feed chambers 84. Packing glands are

preferably provided to receive the lower ends of the sight tubes. The feed nozzles 100 are, at their upper ends, formed to provide valve seats and screw threaded upon the elbows 99 to coöperate with the said seats are manually operable valves 104 adjustable to control the feed of the lubricant to the chambers 84.

Formed in the block 75 to communicate with the feed chambers 84 are discharge passages 105 having check valves 106 arranged therein and screw threaded into the blocks to communicate with the said passages, are lubricant discharge pipes 107 and 108 respectively. The pipe 107 is equipped with an elbow 109 and mounted in this elbow is a check valve 110 adapted to prevent a back flow within the pipe 107 while the valve 106 will prevent back flow within the passage 105 of the block 75. Connected with the elbow 109 is a T union 111 from which extends a pipe 112 fitted into a steam line or pipe 113. Threaded into the adjacent extremity of the elbow 109 and extending through the union 111 and pipe 112 is a pipe 114 discharging into the pipe 113.

Connected with the union 111 is a branch steam pipe 115 leading to a passage through the block 75 and communicating with a steam duct 116 extending within the receptacle 74 down one corner thereof beneath the said block and along one side of the receptacle at the junction of the said seat with the bottom wall of the receptacle. The duct 116 is preferably formed integral with the receptacle and leading from the said duct is a discharge pipe 117. Interposed in the pipe 115 is a shut-off valve 118.

The lubricant discharge pipe 108 is equipped with a check valve 108' and a T union 119 into one end of which is threaded a steam nozzle 120 while a discharge pipe 121 extends from the opposite end of the said union. Threaded into the nozzle 120 is a branch pipe 122 communicating with the branch steam pipe 115 below the valve 118. It is now to be observed that the lubricant discharge pipes 107 and 108 are arranged to parallel the branch steam pipe 115 for a portion of their strength to be heated from the said steam pipe and are connected therewith by bands 123.

Extending transversely through the receptacle 74 and journaled upon the side walls thereof, is a driven shaft 124 and mounted upon this shaft to coöperate with the yoke 88 is a cam 125 identical with the cams 60 of the preferred form of the invention. Connected to the outer end of the shaft 124 is a pawl and ratchet mechanism and rock arm for rotating the shaft by a step by step movement, the said pawl and ratchet mechanism and the said rock arm being also identical with the structure previously de-

scribed in this regard. The reference numerals upon these parts have accordingly been duplicated.

It will now be seen that reciprocation of the yoke 88 by the cam 125 will simultaneously reciprocate the pistons 78 and 85. Reciprocation of the circulating pump system 78 will act to draw the lubricant up through the supply pipe 80 into the circulating pump chamber 77. From this chamber, the lubricant will then be forced up through the passage 81 and past a check valve 126 arranged in the said passage to enter the pipe 94 and flow into the manifold 95. From the manifold, the lubricant will be forced in opposite directions through the nozzles 100 to be regulated in its flow by the valves 104 and into the passages 103 to enter the piston chambers 84. The feed pump pistons 85 will then act to force the lubricant out through the discharge pipes 107 and 108. Lubricant flowing through the pipe 107 will, as will be observed, be discharged from the pipe 114 into the steam pipe 113 while the lubricant flowing through the pipe 108 will be discharged into the steam pipe 121. This provides an arrangement wherein the device may be used in connection with an engine employing high and low pressure cylinders with the pipe 113 leading to the high pressure cylinder and the pipe 121 leading to the low pressure cylinder and it is to be observed that the lubricant will be discharged directly into the said pipes to be delivered to the cylinders. By opening the valve 118, steam will be permitted to flow from the pipe 113 through the pipe 115 and through the duct 116 in the receptacle 74 to maintain the said duct hot. This duct will, therefore, act to keep the lubricant within the receptacle hot so that the said lubricant will always be maintained fluent and since the pipes 107 and 108 are arranged to parallel the steam pipe 115, each for a portion of its length, the lubricant being discharged through the said lubricant pipes, will be again heated before being finally delivered into the steam pipes 113 and 121.

In this connection, it is to be observed that when the valve 118 is open, steam will flow through the nozzle 120 to cause a suction at the adjacent end of the lubricant pipe 108. This suction will tend to draw the lubricant through the said pipe into the union 119 and then force the lubricant through the pipe 121 with the valve 108' acting to prevent any water or condensation from flowing into the lubricant pipe. Excess lubricant pumped into the manifold 95 by the pump 78 may flow back through the pipe 96 and passage 97 into the receptacle.

In Figs. 11 and 12 of the drawings, I have illustrated a still further modification

of the invention which relates more particularly to an amplification of the modification previously described. In this latter modification, an oblong lubricant receptacle 5 127 is employed. Mounted to depend within one end of the receptacle is a body block 128 while a similar block 129 is arranged to depend into the opposite end of the receptacle. Associated with each of the blocks is a 10 circulating pump piston 130 and feed pump pistons 131 corresponding to these parts as associated with the block 75 of the modification previously described. Connecting the pistons of each block is a cross head or bar 15 132. These bars are arranged substantially parallel and are joined by a yoke 133 similar to the yoke 88 of the prior modification. Journalized between the side walls of the receptacle is a shaft 134 similar to the shaft 20 124 and mounted upon the outer end of this shaft 134 is the rock arm and pawl and ratchet mechanism previously described in connection with the preferred form of the invention. Keyed upon the shaft to coöperate 25 with the yoke 133 for reciprocating the cross arms 132, is a cam 135 identical with the cams 60 previously described. Mounted upon the blocks 128 and 129 are the manifolds 136 and 137 respectively. These manifolds 30 are equipped with the feed control valves 138 similar to the valves 104 of the prior modification with the manifolds communicating with the feed chambers of the said blocks in a similar manner. Leading 35 from the manifolds are overflow pipes 138', these pipes being similar to the pipes 96 of the prior modification. The circulating pump of the block 128 is provided with a supply pipe 139 similar to the supply pipe 40 80 while the circulating pump of the block 129 is provided with a supply pipe 140 which may be led to a suitable lubricant receptacle or tank independent of the receptacle 127. Leading through the block 128 is a steam pipe 45 141 which communicates with a duct 142 within the receptacle, this duct being similar to the duct 116 previously described. Communicating with the feed pump chambers of the block 128 are the lubricant discharge 50 pipes 143 and communicating with the feed pump chambers of the block 129 are the lubricant discharge pipes 144. These discharge pipes may be carried off to parallel a main steam line as illustrated in 55 connection with the preferred form of the invention or may be fitted to coöperate with steam pipes similar to the pipes 113 and 121, as illustrated in connection with the modification of invention previously described, the 60 pipe 141, in either instance, of course, being connected with a steam supply pipe.

As will now be observed, this present modification of the invention provides an arrangement wherein one lubricant may be

fed through the pipes 143 from the receptacle 65 127 while a different lubricant may be fed through the pipes 144 from the pipe 140.

Having thus described my invention, what is claimed as new is:

1. A device of the character described including a body having a circulating pump chamber and a plurality of feed pump chambers formed therethrough, pistons mounted to reciprocate in the inner portions of said chambers, means for reciprocating the pistons, a lubricant supply tank communicating with the circulating pump chamber, a manifold connected with the feed pump chambers intermediate the ends thereof and communicating with the outer end of the circulating pump chamber, discharge pipes leading from the outer ends of the feed pump chambers, and a steam pipe extending axially through the manifold and terminating beyond the ends thereof. 70 75 80 85

2. A device of the character described including a body having a circulating pump chamber and a feed pump chamber formed therein, pistons mounted to reciprocate in said chambers, means for reciprocating the pistons, a supply tank communicating with the circulating pump chamber, a connection between the circulating pump chamber and the feed pump chamber, a discharge pipe leading from the feed pump chamber, an overflow pipe leading from the said connection and communicating with the tank, a pressure valve arranged in said overflow pipe, and a pressure dome at the upper end of said pipe. 90 95 100

3. A device of the class described including a body having circulating pump chambers and feed pump chambers formed therein, pistons mounted to reciprocate in said chambers, a supply tank communicating with one of the circulating pump chambers, a second supply tank communicating with the other circulating pump chamber, a manifold connecting the first mentioned circulating pump chamber with some of the feed pump chambers, a second manifold connecting the second circulating pump chamber with the remaining feed pump chambers, means common to both manifolds for closing the inner ends thereof, discharge pipes leading from the respective feed pump chambers, and means for reciprocating the pistons for simultaneously delivering lubricant from both tanks. 105 110 115 120

4. A device of the class described including a body having circulating pump chambers and feed pump chambers formed therein, pistons mounted to reciprocate in said chambers, a supply tank communicating with one of the circulating pump chambers, a second supply tank communicating with the other circulating pump chamber, a manifold connecting the first mentioned circulat- 125

ing pump chamber with some of the feed pump chambers, a second manifold connecting the second circulating pump chamber with the remaining feed pump chambers, 5 means common to both manifolds for closing the inner ends thereof, a heater extending axially through both manifolds, discharge pipes leading from the several feed pump chambers, and means for reciprocating the 10 pistons to simultaneously deliver lubricant from both tanks.

5. A device of the character described including a body having a circulating pump chamber and a feed pump chamber formed 15 therein, pistons mounted to reciprocate in

said chambers, means for reciprocating the pistons, a supply tank communicating with the circulating pump chamber, a connection between the feed pump chamber and the circulating pump chamber, a main steam pipe, 20 a branch steam pipe leading from the main steam pipe and extending axially through the connection between the pump chambers and terminating beyond the ends thereof, and a discharge pipe leading from the feed 25 pump chamber and carried to and along the main steam pipe.

In testimony whereof I affix my signature.

JOHN C. ROSS. [L. s.]
